UNITED STATES PATENT OFFICE.

ALBERT J. MOE, OF SAN PEDRO, CALIFORNIA.

DESIGN FOR A SIGNAL-LIGHT CASING.

Application filed June 10, 1926. Serial No. 18,003. Term of patent 3½ years.

To all whom it may concern:

Be it known that I, ALBERT J. MOE, a citizen of the United States, residing at San Pedro, in the county of Los Angeles and State of California, have invented a new, original, and ornamental Design for a Signal-Light Casing, of which the following is a specification, reference being had to the accompanying drawing, forming a part thereof.

Figure 1 is a side elevation of a signal light casing, showing my new design. Fig. 2 is an end view. Fig. 3 is a bottom plan view of the same. Fig. 4 is a perspective view of my casing.

I claim:

The ornamental design for a signal light casing, as shown.

ALBERT J. MOE.
